mington, Del., a corporation of DelawareNo Drawing. Application August 18, 1932,
Serial No. 629,307

11 Claims. (Cl. 87—16)

This invention relates to soaps and soap-making processes, and more particularly to a new type of superfatted soap and processes for manufacturing the same.

5 This invention is dependent upon and is an out-growth of my discovery of a novel and economical method for the production of fatty alcohols of high molecular weight through catalytic reduction with hydrogen of fatty carboxylic acids 10 and their derivatives as disclosed in Lazier U. S. Patent 1,839,974 and copending applications Serial No. 445,224, filed April 17, 1930, and Serial No. 520,473, filed March 5, 1931.

Soap-making is an art of considerable antiquity 15 and as a consequence has suffered few chemical changes of a fundamental nature in modern times. The introduction of catalytic hydrogenation as a fat hardening process, while profoundly affecting the supply of fatty materials potentially suitable for soap-making, has not resulted in an appreciable alteration in the character of the product produced, since substantially saturated glycerides were already available from natural sources before the discovery of the hardening 20 process. On the other hand such compounds of an alcoholic nature as have been occasionally employed in soap-making have been as a rule and of necessity produced by artificial means by processes that were often prohibitively costly. Various 25 so-called "fillers" such as wax, petroleum products, and ground mineral substances are commonly incorporated into soap as cheapening agents and without meritorious improvement in the quality of the product. On the other hand certain fillers such as rosin and the hydrogenated 30 phenols and naphthols are known to improve the detergent power of the soap and render its use against mineral grease and in hard waters more economical than would otherwise be the case.

40 In 1885 Unna introduced the practice of adding unsaponified fat to soap for the purpose of aiding in the retention of medicinal agents. Various other advantages of "superfattening" have since been recognized, particularly in connection with 45 the manufacture of fine toilet soaps, although the use of fats as originally proposed has given trouble with the development of rancidity. Wool fat or lanolin is less objectionable for this purpose on account of its high content of cholesterol, and 50 has been extensively used as a superfatting material.

It is an object of this invention to improve 55 upon the quality of fine soaps and methods for their manufacture through the application of newly discovered processes for the preparation

of fatty alcohols. A further object is to prepare a new type of superfatted soap wherein the superfatting agent is a fatty alcohol prepared from a fatty acid or its derivative by catalytic hydrogenation. A still further object is to combine advantageously and economically into a unified process the necessary steps required for the preparation of soaps containing higher fatty alcohols as the superfatting agents. Other objects will appear hereinafter.

I have now found in accordance with this invention that the non-cyclic or open-chain synthetic higher alcohols or mixtures of alcohols possessing from 8 to 20 carbon atoms derived from the naturally occurring fatty acids by direct catalytic hydrogenation at high temperatures and pressures are particularly well suited for use as agents for the superfatting of soap and soap products. I have determined further that the processes of catalytically preparing higher alcohols and the processes of soap manufacture are so related as to make it economically and scientifically desirable to combine the necessary operations into a unified process. Broadly considered, the process of my invention may therefore be regarded as a novel method for the manufacture of 10 superfatted soap of a special kind.

In accordance with my invention I may produce a super-fatted soap by taking a semi-finished or stock soap of neutral reaction and high 15 quality and adding thereto an appropriate amount of a fatty alcohol having from 8 to 20 and preferably from 8 to 15 carbon atoms and separately prepared from a fatty acid or fat by catalytic 20 hydrogenation. The mixture of soap and alcohol 25 is then milled until uniform in appearance and texture and is molded in the usual manner.

Alternatively I may add the pure alcohol to the 30 fats or oils prior to saponification or I may carry out a hydrogenation process on a small part of 35 soap stock to convert it rather completely to alcohols, then mix with the remainder of the stock and carry out the saponification. Still another method of carrying out the invention is to subject the entire lot of soap stock fats to a very 40 mild hydrogenation whereby only a small part of the glycerides is converted to alcohols. Where 45 liquid fats are employed that require hardening, the production of a sufficient concentration of fatty alcohols may be obtained simultaneously 50 with the hardening process by carrying out the necessary hydrogenation in the presence of a suitable catalyst and at sufficiently high temperatures and pressures. Having treated the soap 55 stock in such a manner as to produce the

necessary concentration of the corresponding alcohols any one of a number of soap-making processes may be employed, for example, the stock may be boiled with the alkali in the production of 5 a hard grained soap or the saponification may be carried out in such a way as to produce a high-yield semi-boiled soap. Soaps containing fatty alcohols may also be produced from such special stocks by the cold process, i. e., by treatment of the 10 soap stock at temperatures below the boiling point, e. g., the soap stock may be heated to its melting point, and the caustic alkali then added.

Having now outlined in a general way how I carry out my invention I will present specific examples showing in detail how I proceed to practice the invention.

Example 1.—A smooth white toilet soap having good detergent properties is prepared as follows: A fine white boiled stock soap is procured by 20 saponification of fresh odorless tallow containing 10% of coconut oil with sufficient caustic soda to give a product essentially free from salt and unsaponified fat, and containing not more than 0.2% of free caustic soda. One hundred pounds 25 of the stock soap is chipped and milled with 8 pounds of stearyl alcohol (prepared by the hydrogenation of pure stearic acid), 4 pounds of starch and 16 oz. of a suitable perfume blend. When the mass is perfectly homogeneous, the charge is 30 passed through a plodder and cut into cakes which are compressed to bars of suitable shapes. Instead of the milling process the stock soap and the stearyl alcohol may be melted, the other fillers and perfumes added and the charge framed, cut 35 and pressed.

Example 2.—A suitable textile soap filled with molecular weight fatty alcohols is prepared as follows: Mix together with the aid of heating 900 pounds of palm-kernel oil, 600 pounds of cotton-seed oil and 400 pounds of tallow. Withdraw 200 pounds of the mixed fat and subject this portion to catalytic hydrogenation at 385° C. and 2,000 pounds pressure by passing it continuously with an excess of compressed hydrogen over a catalyst 45 consisting of 85 mole % of zinc chromite and 15 mole % of copper chromite. The rate of flow of the oil over the heated catalyst should be about 8 times the catalyst space per hour and the hydrogen-glyceride mole ratio should be about 20. 50 The composition of the processed oil corresponds to about 85% conversion of the fats to the fatty alcohols. The crude hydrogenated oil is added to the main portion or unhydrogenated part and the mixture is run into and boiled with 1555 pounds 55 of caustic soda lye of 30° Bé. The charge is sprinkled with 50 to 100 pounds of 90° Bé. brine, finished with 100 pounds of fresh palm-kernel oil, and allowed to settle, after which it is framed and molded in the usual manner.

Example 3.—A cold process toilet soap containing lauryl and other alcohols is prepared as follows: One hundred pounds of coconut oil is mixed with 8 pounds of copper chromite powder and is heated to 250° C. in a stirring autoclave under a hydrogen pressure of 100 atmospheres until the decrease in the hydrogen pressure corresponds to the theoretical value for hydrogenation of 5-8% of the carboxylic groups in the oil. The oil is cooled, filtered and mixed with 50 pounds 70 of 38° Bé. soda lye in a stirring kettle at a temperature of 35° C. When saponification is complete and the mass commences to thicken, it is perfumed and run off into frames in which it is allowed to congeal slowly. If a low-priced product is being prepared the perfume may be omitted

since the lower boiling members of the coconut oil alcohols contribute a considerable desirable odor to the product.

Example 4.—A castor oil soap is prepared as follows: Castor oil is subjected to catalytic hydrogenation by passing it continuously with hydrogen over a catalyst prepared by coprecipitating the chromates of zinc, copper and cadmium in the molecular ratio of 82.5:10:7.5 and igniting at 600° C. to form the corresponding chromites. The 10 temperature of the hydrogenation is 390° C. and the hydrogen pressure 2700 pounds per square inch. The oil is passed over the catalyst at the rate of 4 times the catalyst volume per hour with a sufficient amount of hydrogen to give 10 15 moles per mole of combined ricinoleic acid. The decrease in the saponification value resulting from hydrogenation of the ester groups is about 60% while the iodine number is lowered from 85 to 55. The product is fluid and is subjected to a second hydrogenation with a reduced nickel catalyst at 150° and 150 pounds hydrogen pressure whereupon the olefinic groups become saturated. The oil congeals to a white solid and possesses a 20 fragrant odor. Analysis of the product at this stage has shown it to contain octadecanediol, 25 stearyl alcohol and certain alcohols of lower molecular weight such as heptyl and undecyl alcohols, together with a residuum of hardened castor oil and synthetic waxes. The product is converted to a highly superfatted soap by saponification with the theoretical amount of caustic soda calculated from the saponification number determined after hydrogenation. Since the content of higher alcohol is higher than normally 30 desired in a commercial superfatted soap, it is convenient to employ a product prepared as just described as a stock material for superfatting soaps from other sources. For example a white 35 stock toilet soap may be admixed with castor soap and octadecanediol by melting or milling it with 10-15% of the octadecanediol stock prepared as described above.

All of the fats and oils now employed for soap-making are applicable to the present invention. 45 These may be of either vegetable or animal origin. The free fatty acids may also be used and the esters of these with alcohols other than glycerol. These may correspond with the existing fats or may be from a synthetic or mineral source such as, for example, the naphthenic acids. The amount of alcohol compounded with the soap stock may vary between wide limits, the preferred amounts ranging between 1 to 50% of the final product.

In carrying out the hydrogenation of the fatty acids, esters, etc., the catalyst may consist of almost any hydrogenating metal such as zinc, copper, cobalt, nickel or platinum or preferably of a difficultly reducible hydrogenating oxide, 60 such as copper oxide in combination with chromium oxide, zinc oxide, or manganese oxide. Suitable temperatures are found in the range of 200-450° C. and suitable pressures above 10 atmospheres.

The fatty materials hydrogenated to produce the higher alcohols may be fatty acids, their esters, amides, salts and chlorides. These materials are all embraced under the term "fatty acids and their derivatives".

The alcohols to be introduced into the soap by the methods outlined are high boiling liquids or solids, usually having straight chains of a considerable number of carbon atoms, say, from 8 to 20 and preferably 8 to 15. Alcohols containing

from 8 to 15 carbon atoms per hydroxyl have the advantage of greater solubility in water and are more valuable as perfume fortifiers than alcohols of too waxy a character. The latter have an oily appearance and are but slightly soluble in water. I have referred to these alcohols as "fatty alcohols" meaning by this that they correspond to fatty acids in which the

10

group has been converted into the $-\text{CH}_2\text{OH}$ group. Furthermore, none of the alcohols used in accordance with the present invention occur naturally either as free alcohols or as esters. They will therefore be referred to as synthetic alcohols, and the scope of the invention will be construed as covering only those alcohols which are prepared by catalytic hydrogenation of the corresponding acid, ester, etc. The more important alcohols within this class are octyl, nonyl, decyl, undecyl, lauryl, tridecyl, myristyl, pentadecyl, palmityl, margaryl, linoleyl, oleyl, hypo-gaetyl, ricinoleyl, stearyl, and nonadecyl.

25 By introducing fatty alcohols into soaps I do not mean to imply that other fillers are necessarily to be replaced or excluded. In addition to the fatty alcohols valuable soaps may contain also such substances as aliphatic, aromatic, or hydroaromatic hydrocarbons, hydrogenated phenols, paraffin and other waxes and resins, naphthalene, drugs, etc.

The advantages of incorporating higher fatty alcohols into soaps and soap products are several. 35 The higher alcohols impart to the soap and to the products washed with it a smooth, soft feel that is not produced in the absence of the alcoholic fillers. Textiles remain, after washing, in a soft, fluffy condition and the effect on the skin 40 is such as is free from the harshness ordinarily resulting from complete removal of the natural oils with ordinary soap. In the use of the fatty alcohols for superfatting, these advantages are gained without risk of rancidity since the fatty alcohols 45 are immune to fermentation processes and probably possess mild germicidal power of their own. In the manufacture of toilet soap the solid higher alcohols increase the capacity of a soap of a required hardness for retaining water, impart an 50 improved grain or texture and result in an improved gloss on the surface of the polished bar. Depending somewhat on the local conditions, the use of the fatty alcohols may be an aid to detergency under the exacting conditions encountered 55 with sea water or other mineral-containing waters. There is an additional advantage connected with the use of the more volatile alcohols derived from the coconut oil acids or prepared by the destructive hydrogenation of castor oil, 60 for these alcohols have strong perfuming qualities. By employing in the soap-making process stocks containing the appropriate oils and subjecting these stocks to a preliminary and partial hydrogenation under conditions suitable for reducing the carboxyl groups to alcoholic groups, 65 the soaps automatically acquire agents that serve to strengthen the perfumes to be added later or render the use of such perfumes wholly unnecessary.

70 A number of advantages and economies are effected by consolidating the steps required for the production of higher alcohols and soaps. In carrying out the hydrogenation of a fat or fatty acid or ester to form alcohols, the reaction is

never complete, making it necessary to subject the crude hydrogenation product to a careful purification and separation in order to isolate the pure alcohol. By combining the hydrogenation with the saponification incident to the soap-making, the unhydrogenated portion of the crude alcoholic product is destroyed without additional expense and with the advantage that an equivalent amount of soap is produced. By subjecting mixed soap stocks to hydrogenation it is possible 10 to vary greatly the character of the fatty alcohols entering the soap and hence alter the properties of the finished article. There is yet another advantage. As already pointed out, it is common practice to harden certain soap fats and it is entirely feasible to produce alcohols during the hardening process and without much extra expense provided suitable temperatures, pressures, and catalysts are selected.

15 I am fully aware that a notable advance in the art of detergency has recently been made through the development and use of sulfonated higher alcohols and hydrocarbons. I lay no claim to any such processes, restricting my invention to the uses of the derived fatty alcohols themselves as 20 adjuncts to soap.

25 The above description and specific examples are illustrative only and are not intended to limit the scope of the invention. Any modification or variation corresponding to the spirit of the invention is intended to be included within the 30 scope of the claims.

I claim:

1. A soap containing an aliphatic open-chain alcohol, having from 8 to 20 carbon atoms, and 35 corresponding to a fatty acid which is contained in naturally occurring fats.

2. The soap described in claim 1, characterized in that the alcohol contains from 8 to 15 carbon atoms.

3. The soap described in claim 1, characterized in that the alcohol is one obtainable from the 40 catalytic hydrogenation of soap stock.

4. The soap described in claim 1, characterized in that the alcohol is one obtainable from the 45 catalytic hydrogenation of coconut oil.

5. The soap described in claim 1, characterized in that the alcohol is one obtainable from the 50 catalytic hydrogenation of castor oil.

6. The soap described in claim 1, characterized 55 in that the alcohol is lauryl alcohol.

7. In a soap-making process the step which comprises commingling a soap and an aliphatic open-chain alcohol, having from 8 to 20 carbon atoms, said alcohol corresponding to a fatty acid 55 which is contained in naturally occurring fats.

8. A soap-making process described in claim 7, characterized in that the alcohol contains from 8 to 15 carbon atoms.

9. The soap-making process described in claim 60 7, characterized in that the alcohol is produced by the catalytic hydrogenation of the corresponding fatty acid.

10. The soap-making process described in claim 65 7, characterized in that the soap is produced from soap stock that is intimately mixed with said alcohol.

11. The soap-making process described in claim 70 7, characterized in that the alcohol is produced by the catalytic hydrogenation of the corresponding fatty acid and the soap is produced in the presence of said alcohol.

WILBUR A. LAZIER.
